FASTENER FOR BOXES OR THE LIKE

Filed March 18, 1931

INVENTOR:
ARTHUR A. WELLER
By: Robert Cushman Woodbury
His Attorney

UNITED STATES PATENT OFFICE

ARTHUR A. WELLER, OF PROVIDENCE, RHODE ISLAND, ASSIGNOR TO THE MASON BOX COMPANY, OF ATTLEBORO FALLS, MASSACHUSETTS, A CORPORATION OF MASSACHUSETTS

FASTENER FOR BOXES OR THE LIKE

Application filed March 18, 1931. Serial No. 523,403.

The invention relates to fasteners for temporarily securing separable portions of a box, envelope or the like, and pertains more particularly to improvements in metallic box 5 fasteners of the deformable type especially suitable for detachably holding the closed cover or lid of a pasteboard box for mailing or other purposes.

The principal purpose of the invention is 10 to provide a simple, economical and efficient fastener of the aforesaid class, in which a bendable tab or loop of ductile wire adapted to be passed through a slot or aperture of the box cover, is so affixed to the side of a box 15 that its exposed portions present smooth, rounded surfaces, thereby avoiding sharp edges or projections which might scratch or injure the hands of the user or catch and damage other articles. The projecting end 20 of the loop is bent or folded over onto the outer surface of the box cover to secure it in closed position, in accordance with common practice.

I am aware that box fasteners have heretofore been devised in which a deformable wire loop serves to retain the closed cover, but it is very difficult to attach such prior fastener to the body of the box without leaving an unprotected end of the wire protruding at 25 the outer side of the box wall. The presence of such projecting wire ends is objectionable not only because of the likelihood of injury to the fingers but also because the ends tend to straighten out during handling and 30 hence loosen the attachment of the fastener.

It is accordingly the main object of the present invention to produce a fastener which retains the several advantages of the previous wire loops while avoiding and remedying 35 the objections above noted. To this end I have devised a two part fastener comprising a loop member of ductile wire and a saddle or cover member applied over the legs of the wire loop and secured to the box wall so that 40 the loop is permanently attached to the box body with its extreme ends concealed and protected either between the box wall and the saddle or by passing the wire ends inwardly through the box wall and clenching 45 them against the inner face thereof.

Further objects reside in the improved features of the several embodiments of the invention hereinafter described in connection with the accompanying drawing, and will be pointed out in the appended claims. It will 55 be understood, however, that structural details of the particular devices chosen for the purpose of illustration may be varied to suit particular purposes without departing from the spirit of this invention; and that the improved fastener may be suitably employed in association with the body and flap of an envelope, in attaching paper sheets to a relatively stiff backer, or in connection with boxes 60 of various materials, size and construction. 65

In the drawing:

Fig. 1 is a perspective view of a box equipped with a preferred form of the improved fastener;

Fig. 2 is a plan view of a separable cover 70 adapted to be fastened upon the box of Fig. 1;

Fig. 3 is an end view of the box with the cover applied, showing in broken lines the usual folded position of the fastener loop;

Fig. 4 is a composite view showing the wire 75 loop and the saddle or cover plate prior to their assemblage and attachment to the box of Figs. 1 to 3;

Fig. 5 is an enlarged section taken on line 80 5—5 of Fig. 1;

Fig. 6 is an elevation of the two parts of a modified form of fastener prior to attachment;

Fig. 7 is a section on line 7—7 of Fig. 6, 85 illustrating the mode of attachment thereof;

Fig. 8 is a fragmentary end view of a box equipped with another modification of the improved fastener; and

Fig. 9 is a section on line 9—9 of Fig. 8. 90

In the particular embodiment of the invention chosen for the purpose of illustration in Figs. 1 to 5, opposite end walls of the box 11 are equipped with a preferred form of the improved fastener which is permanently attached to the body of the box preferably at its upper edge, and which comprises a loop member 12 of ductile wire bent in U-shape and having its lower extremities curled inwardly to provide spaced eyes 13; and a saddle or cover plate 14 applied over the 95 100

legs and eye portions of the loop and fastened to the box wall to clamp the loop member between itself and said wall. The upper or looped portion of the member 12 preferably projects above the edge of the box in the manner of a tab and is adapted to be inserted in complementary slots 15 formed in the box cover 16 and to be bent over as indicated by the broken lines of Fig. 3 to hold the closed cover firmly in position.

The saddle or strap 14 may be conveniently formed from a blank of sheet metal shaped as indicated in Fig. 4 and preferably having side tabs or ears 17 which are bent rearwardly as on the dotted fold lines prior to or during the application of the saddle to the loop legs and box wall. The ears 17 preferably are struck through the box body and clenched within (Fig. 5) or over the inner surface of the box, to clamp the loop in its applied position. When so applied the loop is prevented from longitudinal movement (in a vertical direction) by shoulders or protuberances 18 formed on the inner side of the saddle or plate 14 and engaging in the eyes 13 as shown in Fig. 5. The protuberances may readily be formed by punching rounded detents inwardly of the body of the plate 14 at the regions shown by the broken lines 19 of Fig. 4. The fastener may be applied and secured to the box either by hand or by appropriate machines, and when mechanically affixed the loop may be applied to the box wall, the saddle positioned over the loop legs, the retaining tabs 17 forced into the wall and clenched thereto, and the detents 18 depressed into the eyes 13 by simultaneous or successive operations in a single machine. The fastener members are thus firmly and securely attached to the box and relative longitudinal displacement thereof is effectively prevented by the mutual engagement of the complementary elements 13 and 18 of the loop and saddle respectively. It will be observed that the objectionable presence of sharp wire ends at the outer side of the box is avoided by this arrangement, and that the saddle or plate 14 completely covers the legs and extremities of the loop and not only prevents papers or other articles from catching behind the wire legs but also obviates the possibility of lateral displacement thereof.

In this and the succeeding variations of the improved fastener, the wire loop preferably has offset shoulders 19 disposed above the upper edge of the saddle to provide a predetermined hinge line upon which the upper or tab portion of the loop may be bent over to secure the box cover. Hence, the bending of the tab causes merely a twisting stress at the wire shoulders and avoids the direct shearing strain which is normally imposed upon the straight wire sides of previous loop fasteners. The life of the fastener is thus prolonged, for the tendency of the

wire to break at the bend or fold line is greatly diminished.

In the modification shown in Figs. 6 and 7, the loop 22 has its lower ends 23 bent toward and preferably overlapping each other, and the saddle or cover plate 24 has, in addition to the side tabs 25, a bottom tab 27 which is bent inwardly beneath the wire ends 23 and thence upwardly and outwardly above said ends to provide a shoulder 28 which protrudes over the ends 23, so that the loop is held against longitudinal displacement. Obviously, the shoulder or abutment 28 may consist of a hump of the box material which is pressed outwardly by clenching the tab 26 as aforesaid, or may be formed by the tab end itself in case the tip of the tab is punched entirely through the box wall in its outward course. In this arrangement also the loop legs are completely enclosed and protected, and the side tabs 25 are fastened in the same manner as the tabs 17 of Fig. 5.

The further variation illustrated in Figs. 8 and 9 comprises a loop 32 having its ends 33 bent inwardly and clenched in the box wall, and a saddle or strap 34 consisting of a piece of wire which straddles the legs 35 of the loop and has its inwardly bent ends 36 bent over and clenched within the box wall (Fig. 9) or upon its inner surface.

From the foregoing it is apparent that the improved fastener is simple and economical to manufacture, easy to apply, and convenient and efficient in use; that it is characterized by the absence of projecting or uncovered wire ends particularly at the outer surface of the box or other article to which the fastener is applied; and that it possesses the many advantages of prior loop fasteners without their objectionable insecurity and risk of injury to the hands of the user.

I claim:

1. A fastener permanently attached to the body of a box and adapted to be detachably secured to a slotted cover for the box, comprising a loop member formed of a single piece of ductile wire having parallel legs applied against the outer surface of the box, and a saddle straddling said legs and covering the ends of said legs, the saddle having retaining portions engaging the box body to clamp the loop legs therebetween.

2. A fastener permanently attached to the body of a box and adapted to be detachably secured to a slotted cover for the box, comprising a loop member formed of a single piece of ductile wire having parallel legs applied against the outer surface of the box, and a cover plate straddling the legs and applied over the end portions thereof, said plate having retaining ears struck through the box body at opposite sides of the loop and engaging the inner surface of the body to clamp the loop legs between the plate and body.

3. A box fastener of the class described comprising a loop member formed of ductile wire having parallel portions applied to the side of a box, a saddle embracing the leg portions and covering the end portions of the loop member to clamp it against the box, and complementary elements carried by the loop and saddle for preventing longitudinal displacement of the loop.
- 10 4. A box fastener of the class described comprising a loop member formed of ductile wire applied to the side of a box, and a saddle embracing and covering the end portions of the loop member to clamp it against the box, said end portions having eyes disposed behind the saddle and the saddle having protuberances engaging said eyes to prevent longitudinal displacement of the loop member.
- 15 5. A box fastener of the class described comprising a loop member formed of ductile wire applied to the side of a box, and a saddle embracing and covering the end portions of the loop member to clamp it against the box, the extremities of said legs being looped upon themselves and the saddle having inwardly struck detents engaging said looped extremities to prevent longitudinal displacement of the loop member.
- 20 6. A box fastener of the class described comprising a loop member formed of ductile wire applied to the side of a box, and a saddle embracing and covering the end portions of the loop member to clamp it against the box, the end portions of the loop member being bent toward each other into juxtaposed overlapping relation, and the saddle having a retaining tab entering the box side below the loop ends and curling upwardly and outwardly above said ends, thereby to provide a transverse shoulder engaging therewith to prevent longitudinal displacement of the loop member.
- 25 7. A box fastener of the class described comprising a loop member formed of ductile wire and having substantially parallel legs terminating in integral eyes, said member being applied to the outer side of the box, and a cover plate secured over the ends of the leg portions, said plate having side ears clenched through the box body and having inwardly struck protuberances received within said eyes.
- 30 Signed by me at Attleboro Falls, Mass.,
35 (Bristol County), this 16th day of March,
40 1931.
- 45 ARTHUR A. WELLER.

DISCLAIMER

1,864,780.—*Arthur A. Weller*, Providence, R. I. FASTENER FOR BOXES OR THE LIKE. Patent dated June 28, 1932. Disclaimer filed July 23, 1935, by the assignee, *The Mason Box Company*.

Hereby enters this disclaimer to claims 1 and 2 thereof, which are as follows:

“1. A fastener permanently attached to the body of a box and adapted to be detachably secured to a slotted cover for the box, comprising a loop member formed of a single piece of ductile wire having parallel legs applied against the outer surface of the box, and a saddle straddling said legs and covering the ends of said legs, the saddle having retaining portions engaging the box body to clamp the loop legs therebetween.

“2. A fastener permanently attached to the body of a box and adapted to be detachably secured to a slotted cover for the box, comprising a loop member formed of a single piece of ductile wire having parallel legs applied against the outer surface of the box, and a cover plate straddling the legs and applied over the end portions thereof, said plate having retaining ears struck through the box body at opposite sides of the loop and engaging the inner surface of the body to clamp the loop legs between the plate and body.”
